CONTAINER VACUUMIZING AND CLOSING MACHINE

Alfred L. Kronquest, Syracuse, N. Y., assignor to
Continental Can Company, Inc., New York,
N. Y., a corporation of New York

Application August 14, 1941, Serial No. 406,899

9 Claims. (Cl. 226—82.4)

The invention relates to new and useful improvements in a machine for vacuumizing and closing containers filled with beverage or food stuffs.

An object of the invention is to provide a simple and efficiently operable machine structure embodying a single closing station, means for feeding filled containers to the station and vacuumized and closed containers from said station, a closing mechanism at said station, means for forming a restricted vacuum chamber about the closing mechanism, and novel means for sealing the chamber while the containers are being vacuumized therein.

Another object of the invention is to provide a machine of the character stated in which the chamber sealing means includes yieldable gripper sectors engageable in sealing contact with the exterior surfaces of containers being presented for vacuumizing and closing, and novel means for actuating said sectors.

Another object of the invention is to provide a machine of the character stated in which the gripper sector actuating means includes an oscillatable actuator ring and movement transmitting lever connections effective to move the sectors toward and from the container gripping position always in generally concentric relation to the container exterior circle.

Another object of the invention is to provide a machine of the character stated in which there is included a container rounding ring through which the containers are forced upwardly into proper position in the vacuumizing and closing chamber, said ring being disposed immediately beneath the container gripping and chamber sealing sectors.

With the above and other objects in view that will hereinafter appear, the nature of the invention will be more fully understood by following the detailed description, the appended claims, and the several views illustrated in the accompanying drawings.

In the drawings:

Figure 1 is a central vertical cross sectional view illustrating a machine embodying the invention, the container lifting and lowering pad being illustrated in its normal, lowered position.

Figure 2 is an enlarged fragmentary vertical cross section illustrating the container lifting and lowering pad elevated to present a container in position for being vacuumized, the container gripping and vacuumizing chamber sealing segments being shown in gripping engagement with the upper portion of a container.

Figure 3 is a horizontal section taken through the machine at a plane just beneath the bottom of the vacuumizing and sealing head.

Figure 4 is a fragmentary face view illustrating the container feed-in and feed-out table portions of the machine.

Figure 5 is a detail vertical cross section taken on the line 5—5 on Figure 4.

Figure 6 is a detail vertical cross section taken on the line 6—6 on Figure 4.

Figure 7 is a detail vertical cross section taken on the line 7—7 on Figure 4.

Figure 8 is a detail vertical cross section taken on the line 8—8 on Figure 4.

Figure 9 is a detail vertical cross section taken on the line 9—9 on Figure 4.

Figure 10 is a detail vertical cross section taken on the line 10—10 on Figure 4.

Figure 11 is a fragmentary vertical cross section taken on the line 11—11 on Figure 1.

Figure 12 is a fragmentary vertical cross section taken on the line 12—12 on Figure 1.

Figure 13 is a part plan and part horizontal sectional view of the machine, the section portion being taken substantially on the line 13—13 on Figure 1.

Figure 14 is an enlarged fragmentary plan view and part horizontal section illustrating the means for controlling the position of the clutch throw out couple member.

Figure 15 is a fragmentary sectional view taken substantially on the line 15—15 on Figure 14.

Figure 16 is an enlarged fragmentary face view illustrating the mounting of the vacuum controlling valve, the bearing equipment for the lower end of the bifurcated coupler carrying rock shaft being shown in section.

Figure 17 is an enlarged fragmentary, somewhat diagrammatic horizontal section illustrating the mounting of the valve action controlling coupler, the coupler being illustrated in its normal uncoupled position just prior to coupling thereof by engagement of the setting devices by a container about to be placed at the closing station.

Figure 18 is a detail cross section taken on the line 18—18 on Figure 16.

Figure 19 is a horizontal section taken through the ring seat in the bottom of the vacuumizing and sealing head body and the chambered ring mounted therein, the container gripping segments being illustrated in their container gripping or inwardly moved positions.

Figure 20 is a somewhat diagrammatic horizontal cross sectional view showing the means

for oscillating the gripper segment actuator ring.

Figure 21 is a fragmentary vertical cross section taken on the line 21-21 on Figure 20.

Figure 22 is a fragmentary vertical cross section illustrating the cam actuated rocker shaft associated with the gripper segment actuator ring oscillating devices.

Figure 23 is a development of the container lifting and lowering pad actuating cam.

In the example of embodiment of the invention herein disclosed there is included a main frame having a base 5, a main body portion 6 flange-secured on the base, as at 7, and a superstructure 8 extending upwardly from said main body portion and flange-secured thereon as at 9. A drive top housing 10 is flange-secured on the superstructure 8, as at 11, and its upper extremity is closed by a removable cover plate 12. See Figure 1.

A main rotary shaft 13 is disposed uprightly in the frame in a bearing 14 provided therefor in the base 5, in a bearing 15 provided in the main body portion 6, and in a bearing 16 in a drive sleeve 17 which is in turn mounted in anti-friction bearings 18 in a bearing well 19 carried by the top housing 10. The shaft 13 normally rotates with the sleeve 16, 17 but is capable of remaining stationary independently of this sleeve under overload conditions to be described hereinafter. See Figure 1.

At its lower end, the shaft 13 has a container feed driving bevel gear 20 affixed thereto, and the gear and shaft are supported on an anti-friction end bearing 21 provided in the base 5. See Figures 1 and 12. Just above the bearing 14 a sleeve 22 is keyed to the shaft 13, and the upper end of this sleeve carries a driver gear 23, the purpose of which will later become apparent. A pad lifter cam 24 surrounds the sleeve 22 and is secured to rotate therewith as at 25. This cam is equipped with a peripheral, pad lifting and lowering groove 26 which will be referred to in detail hereinafter. See Figure 23.

Above the bearing 15 a sleeve 27 is keyed upon the shaft 13, and this sleeve carries and is surrounded by a valve drive couple displacing cam 28, the purpose of which will later become apparent. See Figures 1, 2, 3 and 17. Above the sleeve 27 a sleeve 29 is splined to the shaft, said sleeve 29 being surrounded by a vacuum chamber defining sleeve 30 fitted in a center bore in the container vacuumizing and seaming head casing 31. The sleeve 29 depends from a cam cylinder 32 which is supported in anti-friction end thrust bearings 33 in the casing 31. See Figure 2. The cam cylinder is provided with a peripheral valve actuating groove 34 and a similar knockout pad actuating groove 35, the purposes of which will be more clearly described hereinafter. A sleeve and cover plate cam 36 surmounts the open top of the cam 32, and the upper extremity of the sleeve portion abuts an anti-friction bearing 37 provided in the cover plate 38 mounted at the top of the casing 31. See Figures 1 and 11.

An abutment plate 39 is affixed to the upper end of the shaft 13, and an overload release drive collar or ring 40 is splined on said shaft so as to rotate therewith and yet be capable of vertical sliding movement thereon. The collar 40 is equipped with three equidistantly spaced driving rollers 41 having their axes disposed radially with respect to the axis of the shaft 13 and being engageable in seats 42 in a driver disk 43 carried at the upper end of the sleeve 17

hereinbefore referred to. The collar 40 is constantly urged downwardly, to be thereby yieldably held in driving contact with the disk 43, by compression spring equipment 44 interposed between said collar and the abutment plate 39. See Figure 1.

The disk 43 carries a clutch throw out effecting lug 45 and has a worm gear ring 46 secured thereon. Rotation is imparted to the worm gear ring 46 and through the disk 43 and the collar 40 to the main shaft 13 by a worm gear 47 keyed upon a drive shaft 48 which is rotatable in bearings 49 in a drive housing 50 suitably supported at the upper portion of the machine framing. See Figures 1, 11 and 13. A driving pulley 51 is freely rotatable about the shaft 48 and has rotation imparted thereto by V-belt equipment 52 from a pulley 53 secured upon the armature shaft of a motor 54 which is supported at the top on the machine framing. The pulley 51 has a cone clutch face which is engaged by a cone clutch member 55 splined on the drive shaft 48 as at 56. The clutch member 55 is normally held clutched against the pulley 51 by a spring equipment 57 interposed between the hub of the hand wheel 58 fixed to the sleeve of said clutch member and an abutment head 59 which is secured upon the shaft 48.

A clutch shifting lever 60 is pivoted, as at 61, in the housing and includes a yoke portion trunnion connected with the shifter ring 62, said lever being effective to shift the clutch member 55 against the compression of the spring equipment 57 to thereby release the driving connection and cause the clutch member to engage the brake surface 63 provided on the housing, thereby to discontinue rotation of said clutch member. The shaft 48 also carries a bevel driver gear 64, the purpose of which will later become apparent. See Figures 11 and 13.

In the center of the top housing cover 12 there is provided an upstanding boss 65 about which a clutch shifter ring 66 is oscillatably mounted. A pivot pin 67 is secured in the boss, and a second shifter ring 68 is oscillatable about this pin atop the ring 66, said ring 68 being adjustably secured, by arcuate slot and screw equipment 69, to the underlying ring 66. A lever fulcrum bracket 70 is oscillatable about the pin 67 and pivotally supports a manual clutch shifter lever 71 having a latch lug 72 receivable in a notch 73 in the ring 68. A spring 74 attached to the bracket and to the lever normally holds the lever in an elevated position in which the latch lug 72 is disengaged from the notch 73. See Figure 1.

It is to be understood that whenever the lever 71 is forced down so as to engage the latching lug 72 in the notch 73, and is then swung about the axis of the pin 67, it will serve to turn the rings 66 and 68 and manually effect a disengagement of the clutch member 55 and a resultant stoppage of the machine. For this purpose the ring 68 is provided with a crank extension 75 which is connected by a link 76 with a crank 77 secured upon the upper end of a rock shaft 78. The rock shaft 78 is rockably mounted in frame bearing equipment 79 and carries a crank 80 at its lower end which is link-connected, as at 81, with the clutch shifter lever 60. The crank and link connections 81 act as a toggle lock when shifted slightly past the dead center position, thereby to hold the clutch lever in the clutch release position following each machine operation stoppage until the lever is intentionally shifted to again initiate operation of the machine. It is

to be understood, of course, that the motor 54 operates continuously during all temporary stoppages of the machine. See Figures 1 and 13.

It is also contemplated that the clutch shall be disengaged and the machine automatically stopped whenever a jam in the machine imposes an overload upon the driving connections herein-after described in detail. For this purpose the overload release drive collar 40 which is free to move upwardly on the shaft 13 to unseat the driving roller equipment 41 whenever the machine becomes jammed engages the lower end of a thrust pin 82 which is vertically-slidably mounted, as at 83, in the cover 12. The pin 82 carries an abutment head 84 at its upper end and this head underlies one end of a rock lever 85 pivoted intermediate its ends, as at 86, and having its other end equipped with a depending tappet 87. The tappet 87 is engageable with a plunger 88 vertically slidable in a rock shaft 89 having bearing, as at 90, in the housing and carrying a grooved carrier head 91 at its lower end. See Figures 1, 14 and 15. Within the downwardly directed groove in the head 91 there is mounted a shift-able coupling member 92 which is pivoted, as at 93, to the lower end of the plunger 88 and has an end portion thereof extended inwardly in position for overlying the path of travel of the clutch throw-out lug 45. A spring 94 surrounding the plunger 88 in a bore enlargement in the shaft 89 normally holds the plunger in its elevated position with the coupling member 92 disposed well above the path of travel of the clutch throw-out lug 45. It will be obvious that each time the overload release collar 40 is moved upwardly to break the drive connection between the driven worm ring 46 and the main shaft 13, the pin and lever equipments 82, 85 will act to depress the plunger 88 and cause the inwardly extended end of the coupling member 92 to be depressed into the path of travel of the clutch throw-out lug 45. When the lug 45 rotating with the disk 43 engages the depressed end of the member 92 it will impart a rocking motion to the shaft 89, and this motion will be effective through suitable crank and link connections to shift the clutch lever 60 and bring about a disengagement of the clutch member 55 and a stoppage of all machine parts other than the idly running motor and drive pulley 51.

The coupling member 92 is extended outwardly beyond its pivotal connection with the plunger 88, and a compression spring 95 is interposed beneath this extended end and a supporting shelf carried by the head 91. By reason of this equipment, should the plunger 88 be depressed at a time when the clutch throw-out lug 45 is immediately beneath the coupling member 92, said member 92 may engage on top of the lug and the spring 95 will take up the thrust of the plunger 88 so as to avoid breakage of parts and will thereafter cause the coupling member 92 to snap down into its intended position in the path of travel of the lug 45. See Figures 1, 14 and 15.

For the purpose of utilizing the rocking motion of the shaft 89 to disconnect the clutch, the shaft 89 is provided at its upper end with a crank 96 which is link-connected, as at 97, with a crank 98 secured upon the shaft 78 hereinbefore referred to and which is crank and link connected, as at 80, 81 with the clutch lever 60. The link 97 is slotted, as at 99, at the point of its connection with the crank 98 so as to permit manual operation of clutch 55 without affecting the overload disengagement mechanism. See Figure 13.

Suitably supported on the machine framing is a container body infeed table 100 and an outfeed table 101 including a downwardly inclined portion 102, and in the space provided therefor intermediate these two aligned feed tables 100, and 101 and herein designated a closing station 103, there is provided a vertically reciprocable container lifting and lowering pad generally designated 104. See Figures 3 and 4.

10 The infeed table 100 includes supporting ways 105 which are recessed to accommodate two laterally spaced block chains 106, onto which the filled containers 107 are fed by a suitable conveying line (not shown), and a single intermediate disposed chain 108 provided with equidistantly spaced filled can driving lugs 109. The supporting ways 105 are flanked at one side by fixed walls 110 and a yieldably mounted wall 111, the latter being opposed at the opposite side of the ways by a timing screw 112 having trunnion bearing, as at 113, in the screw housing 114 mounted upon the infeed table. The timing screw serves a purpose well known in the art, namely, that of intercepting filled containers fed onto the ways 105 and equidistantly spacing them for conveying engagement by the chain lugs 109. See Figures 3 and 4.

15 Beyond the screw 112 there are provided filled container supporting ways 115 which extend to the closing station 103. These ways are flanked at the screw side by a fixed wall 116, and at the opposite side by a wall 117, and it will be observed that these walls are jogged laterally, as at 118, to laterally transfer the filled cans from a feed line centered between the chains 106 to a slightly-laterally disposed feed center line centered on the conveyor pins 119 projecting vertically from one of the flights of an endless conveyor chain 120, said pins moving in a clearance 121 provided therefor between the supporting ways 115. The chain 120 travels about sprockets which are rotatable about vertical axes and mounted and driven in a manner later to be described.

20 The screw 112 is driven through a bevel gear couple 122 by a stub shaft 123 which is rotatable in a bearing 124 provided therefor in the housing 114, and the shaft 123 also carries a spur gear 125 which meshes with and is driven by a long spur gear 126. The spur gear 126 is adjustably secured, as at 127, on a sleeve 128 which is keyed on a shaft 129 rotatable in feed-in table bearings 130. The shaft 129 carries sprockets 131 over which the block chains 106 travel. The chains 106 are engaged by tightening sprockets 132 and 25 pass over sprockets 133 mounted on the shaft 134 which is supported, as at 135, on the feed-in table, and one of the chains 106 is extended beyond the other and is looped over a driver sprocket 136 affixed to a shaft 137 which is rotatably supported, as at 138, on the feed-in table. The shaft 137 also carries a driver sprocket 139 about which one end of the lug-equipped chain 108 travels, the other end of said lug-equipped chain passing over an adjustably mounted idler sprocket 140. See Figures 5 to 8.

30 A gear 141 is affixed to the shaft 137 and is driven by a gear 142 mounted on the shaft 143 having bearing, as at 144, in the feed-in table. The shaft 143 is driven by a bevel gear couple 145 from the shaft 146 having rotative bearing, as at 147, in the feed-in table and also being equipped with an adjustably mounted sprocket 148 to which rotation is imparted by a chain 149 which takes over an idler sprocket 150 and over a driver sprocket 151 secured upon the shaft 152

which is rotatable in a frame bearing 153. The shaft 152 also carries a bevel gear 154 to which rotation is imparted by the bevel gear 20 hereinbefore referred to, and thus the filled container feed-in devices are driven in properly timed relation with the vertically disposed main shaft 13 which turns once for each container presentation and closing function. See Figure 12.

The pin chain 129 takes over an idler sprocket 155 mounted on a vertically disposed stub shaft 156 fixed, as at 157, on the feed-in table, and over a driver sprocket 158 similarly mounted on a vertical shaft 159 which is rotatable in a bearing 160 provided in the feed-in table and which is driven by a bevel gear couple 161 from the shaft 162. The shaft 162 is rotatable in a bearing 163 provided therefor in the feed-out table, and the bevel pinion rotatable with this shaft is secured, as at 164, to a driver sleeve 165 key-secured to said shaft. The shaft 162 also carries a driver sprocket 166. See Figures 8 and 9.

The feed-out table 101, 102 is flanked by closed can guiding rails 167 and is provided with a longitudinal slot or way clearance for permitting free movement of the can feeding lugs 168 projecting in equidistantly spaced relation from the feed-out chain 169 which takes over idler sprockets 170 and 171, over an adjustably mounted driver sprocket 172, and over an adjustable tightener sprocket 173. The sprocket 172 is carried by a shaft 174 rotatable in bearings 175 in the feed-out table, said shaft also being equipped with a sprocket 176 to which rotation is imparted by a chain 177 which passes over the driver sprocket 166 hereinbefore referred to. See Figures 3, 4, 9 and 10.

The shaft 162 is driven by a bevel gear couple 178 and a spur gear 179, the latter being rotatable about a shaft 180 supported in the housing part 6 and meshing with and being driven by the spur gear 23 hereinbefore referred to as mounted on the main shaft 13 and secured to the pad lifting and lowering cam 24. The spur gear 179 meshes with and imparts rotation to a spur gear 181 secured upon a spline sleeve 182 which is rotatably mounted, as at 183, in the housing part 6 and through which passes a vertically disposed spline shaft 184 which may constitute a part of the driving mechanism for a cover feed and marker mechanism of any approved type (not shown). It is to be understood that cover feeding mechanisms capable of delivering can end closures one by one onto the open tops of the filled cans presented at the closing station 103 are well known in the art and any approved form may be employed. See Figure 9.

The filled container lifting and lowering pad generally designated 104 includes a head 185 having a depending stem portion 186 which is bifurcated, as at 187, to straddle the pin chain 120 and thereby permit lifting and lowering movement of the pad without interference with said chain. Wear plates 188 are removably secured upon the pad and provide the surfaces upon which the cans directly rest while they are being vacuumized and closed. In order to aid in preventing rotational displacement of the containers while they are being sealed, the upper or container bottom engaging surfaces of these plates are roughened. It will also be observed that the plates 188 are spaced apart laterally so as to permit freedom of movement of the container conveying pins 119 which project vertically from the conveyor chain 120.

In order to additionally hold the containers 75

while they are being vacuumized and sealed and also to assure downward movement of the closed containers with the pad 104 after the vacuumizing and sealing operation, they are provided two jaws which engage the sides of the containers and overlie the bottom seams thereof, one jaw 189 being a fixed jaw and the other jaw 190 being a movable jaw. The movable jaw 190 is normally held open or spaced from a container engaging position on the pad 104 by a spring equipment 191. In order to close the jaws against a container positioned on the pad, the movable jaw 190 is engaged at the proper time by a tappet 192 adjustably mounted at the upper end of the jaw actuating arm 193 which is pivoted intermediate its ends, as at 194, on the head 185. A spring 195 interposed between the lower end of the arm 193 and an abutment 196 carried by the stem portion constantly tends to swing the lower end of the arm outwardly and cause the tappet 192 to force the movable jaw to its container engaging position. A cam 197 fixed on a frame portion 198 engages a roller carried at the lower end of the arm 193 each time the pad is lowered to its normal position and serves to swing the arm inwardly and retract the tappet so that the spring equipment 191 can act to move the jaw 190 to its open position. Thus each time the pad 104 is lowered to its filled container receiving position the jaws 189 and 190 are separated, and each time the pad is lifted the arm will ride above the effective portion of the cam 197 and the spring 195 can act to effect a clamping of said jaws. See Figures 1 and 2.

The pad structure includes a mounting head 199 at the lower end of the stem portion 186, and this head is recessed, as at 200, to receive a plunger head 201, said heads being secured together by a bolt equipment 202, a slight clearance being provided at 203 between said heads so as to permit a slight amount of downward yield movement of the head 200 relative to the plunger head 201. A socket 204 is formed in the stem portion 186 and slidably receives a plunger sleeve 205 threadably mounted on an adjuster screw 206 having an enlargement 207 seated, as at 208, in the plunger head 201. A screw and slot equipment 209 prevents turning of the sleeve 205 and it will be obvious that by adjustment of the screw 206 the degree of compression stored in the spring 210 mounted in the socket 204 above the sleeve 205 can be varied. The spring 210 tends to maintain the yieldably spaced relation of the heads 199 and 201.

A plunger 211 depends from the plunger head 201 and carries a roller equipment 212 which engages in the pad end lifting and lowering groove 26 of the cam 24. The thrust on the cam 24 directly beneath the plunger 211 is opposed by an anti-friction bearing 213 secured, as at 214, on the base 5.

The pad lifting and lowering groove 26 and the cam 24 is provided with a holdown dwell portion 215 extending about approximately 112° of the circumference of the cam. This groove also includes a first stage lift portion 216 which serves to lift the pad so as to present the can to a can rounding throat to be referred to in detail hereinafter, and a second stage lifting portion 217 which follows a 2° dwell and which extends about approximately 26° of the circumference of the cam. The second stage lift serves to lift the pad so as to present the can in position for being vacuumized, and this lift is followed by a dwell portion 218 which extends about approximately

66° of the circumference of the cam, said dwell serving to maintain the position of the parts during the can vacuumizing interval. The dwell 218 is followed by a third stage lift portion 219 which is comparatively slight and extends over approximately 6° of the circumference of the cam. This third stage lift is sufficient to chuck the can following the vacuumizing interval and is followed by a constant, very slight rise lifting portion which extends about approximately 45° of the circumference of the cam. As stated, this lift portion 220 effects only a slight rising of the pad 104, this rise approximating .018 of an inch. The slight rise portion 220 is followed by a dwell portion 221 which extends about approximately 36° of the circumference of the cam, and this dwell is followed by a pad lowering portion 222 which extends about approximately 45° of the circumference of the cam and returns the pad to its normal, lowered position where it is held for an interval of time by the dwell portion 215 hereinbefore referred to. See Figure 23.

Directly over the closing station 103, the vacuumizing and seaming head supporting casing 31 is equipped with a cylindrical suspension bearing portion 223 in which a sleeve 224 extending upwardly from the vacuumizing and sealing head 225 is mounted. The body 226 of this head is flange-secured, as at 221, to the head 225 and provides therein a limited volume vacuumizing and sealing chamber 228. See Figures 1 and 2.

The chamber 228 communicates through a wall port, 229 which is sealed against atmospheric pressure, as at 230, with a vacuum chamber 231 formed within a portion of the casing 31 and sealed off at the inside by the sleeve 30. This casing portion is also provided with a vacuum chamber 232 which is connected in any approved manner with a vacuum source (not shown). The vacuum chambers 231 and 232 are closed at one side by a valve slide plate 233 which is equipped with two ports 234 and 235, the former leading from the chamber 232 and the latter leading into the chamber 231. A D-valve 236 is slideable against the plate 233, the recess in said valve constantly communicating with the vacuum chamber 232 and serving to connect that chamber with the chamber 231 through the ports 234 and 235 whenever the valve is moved to its lowered position. Whenever the valve is thus lowered, the chamber 231 will be evacuated through the ports 235 and 234 and the vacuum chamber 232. See Figures 1, 2 and 16.

The valve 236 is vertically slidably supported at the lower end of an actuator 237 which is vertically slidable in a slide bearing 238, and said valve is normally urged to the upper limit of its travel by spring equipments 239 so as to be normally held in its upper position in which the recess in the valve communicates only with the upper port 234 and the vacuum chamber 232. At its upper end the actuator 237 is equipped with a roller 240 which engages in the valve actuating cam groove 34 hereinbefore referred to. The slide-guided upper portion of the actuator is rectangular in horizontal cross section but the lower portion thereof which extends beneath the slide bearing 238 when the actuator is in its uppermost position is round in horizontal cross section, thereby providing an abutment or thrust shoulder 241 at the lower extremity of said rectangular actuator portion. See Figures 2, 16 and 17.

Whenever the valve 236 is in its uppermost po-

5 sition its upper extremity is spaced below the actuator shoulder 241 a distance sufficient to receive between it and said shoulder a bifurcated coupler 242 formed on the end of an arm 243 secured to a rock shaft 244. The rock shaft is rockably mounted at its upper end in a bracket 245 which is secured, as at 246, to the valve slide 236 so as to be movable therewith, said valve and slide being slidably guided, as at 247, on the casing 31. The shaft 244 is also rockably mounted at its lower end in a bearing 248 which is secured to the framing superstructure 8, said lower end being splined in a sleeve 249 which is rockable in said bearing 248. The sleeve carries a crank 250 which is equipped with a spring pressed detent 251 engageable in recesses 252 in the bearing bracket 248, said detent and recess equipment serving to hold the crank in one or the other of the two positions between which it is oscillated. The crank 250 is link-connected, as at 253, with the container way flanking wall 254 which is pivotally mounted, as at 255, in position for normally intercepting and being deflected by the containers as they are individually moved to the closing station 103. The link 253 is provided with spaced apertures 256 between which an end of the resetting arm 257 engages. The arm 257 is pivotally supported, as at 258, on the base of the frame superstructure 8 and includes an extended portion equipped with a roller 259 which is disposed in the path of movement of the valve equipment resetting cam 28 rotatable with the main shaft 13 and which has been referred to hereinbefore.

It will be obvious that downward movement imparted to the valve actuator 237 will be transmitted to the valve only when the coupler member 242 straddles the rounded lower portion of the actuator and is in abutting relation with the shoulder 241 and the upper extremity of the valve 236. Whenever this coupler is displaced from this position the actuator moves idly without imparting any movement to the valve 236, and this coupler member 242 will always be displaced from its effective or movement transmitting position when no container is present on the feedways and in position for engaging and displacing the flanking wall 254. Moreover, each time the wall 254 has been deflected by movement of a container, thereby to couple the valve and bring about movement thereof and a temporary communication between the vacuum chambers 231 and 232, the cam 28 will act to restore the said wall and the coupler member 242 to their normal positions previously referred to. See Figures 2, 16 and 17.

Within the vacuumizing and sealing chamber 228 there is mounted a chuck 260 which forms a part of the seaming mechanism, said chuck being 60 stationarily suspended at the bottom of a sleeve 261 which is fixed, as at 262, at its upper end in the cover plate 38. Within the sleeve 261 a knockout rod 263 is reciprocably mounted, and this rod carries the usual knockout pad 264 at its lower end. At its upper end the rod is extended above the sleeve 261 and is connected, as at 265, with a guide rod 266 which is reciprocable in bearings 267 in the casing 31 and cover plate 38 and is trunnion connected, as at 268, with the bifurcated end of a lever arm 269. See Figures 1 and 11. The arm 269 is pivotally supported intermediate its ends, as at 270, and is link-connected at its upper end, as at 271, to a slide 272 which is vertically reciprocable in guides 273 provided therefor in the casing 31,

said slide being equipped with a roller 274 which is engaged in the knockout rod actuating cam groove 35 in the cam 32 hereinbefore referred to.

The sleeve 261 is surrounded by a cam sleeve 275 which is rotatable in a bearing 276 in the part 223 of the casing 31. This sleeve has a seaming lever actuator cam 277 secured upon its lower end and carries a driving gear 278 at its upper end. A seaming rotor sleeve 279 surrounds the sleeve 275 and is rotatable in bearings 280 provided therefor in the sleeve 224. The rotor sleeve 279 has a driving gear 281 affixed to its upper end, and the seaming rotor proper 282 is carried at the lower end of this sleeve and within the vacuumizing and seaming chamber 228. The head or rotor 282 carries seaming arm and roller equipment generally designated 283 and which is controlled by the rotary cam 277. It is to be understood that the present invention is not limited to the provision of any particular form of seaming mechanism since various forms of seaming heads may be employed in the vacuumizing and seaming chamber 228. An example of an acceptable form of seaming mechanism is disclosed in U. S. Letters Patent 2,025,061 issued to Alfred L. Kronquest on Dec. 24, 1935. Since seaming mechanisms of this character are well known and are disclosed in detail in the patent referred to, further detailed description of the construction and operation of such seaming mechanisms is thought to be unnecessary. See Figures 1 and 2.

In an extension portion 284 of the casing 31 a spline sleeve 285 is rotatably supported in bearings 286. This sleeve slidably receives a spline shaft 287 which extends vertically from the casing portion 284 into the drive top housing 10, 50 wherein it is supported in bearings 288 and carries a bevel pinion 289 which meshes with and is driven by the drive bevel gear 64 hereinbefore referred to. The sleeve 285 is flange-secured, as at 290, to a driver gear 291 which meshes with and drives the seaming rotor gear 281, and the sleeve 285 is surrounded by a sleeve 292 which carries a gear 293 meshing with and driving the cam gear 278. It will be noted also that the sleeve 292 is secured, as at 284, to turn with the gear 291 and the spline sleeve 285. See Figures 1 and 11.

At the bottom of the vacuumizing and seaming chamber 228, and in the casing body 226, there is formed a seat or counterbore 295 in which is removably secured a chambered ring composed of a recessed body plate 296 and a removably attached bottom plate 297. The plates 296 and 297 of the chambered ring have registering, container passing center openings 298, and this chambered ring is removably secured on the seat 295 and against a sealing gasket 299 by a bottom plate 300 which is removably secured to the casing body 226. The bottom plate 300 is equipped with a central aperture in which is mounted a container rounding ring 301 which is effective to round up any containers which might be slightly out of round as they are being moved upwardly into the vacuumizing and seaming position. See Figures 1, 2 and 19.

Within the chamber of the chambered ring there is oscillatably mounted a container grip actuating ring 302 which includes a driving tooth or recess equipment 303 at one portion of its periphery opposite an opening provided through the casing body 226 through which is projected a toothed sector 304 which engages in the recess

5 equipment 303 of the ring 302. The sector is clamp-secured, as at 305, on the threaded lower end of a rock shaft 306 which is rockably mounted in bearings 307 secured to the casing body 226 and is composed of upper and lower sections adjustably coupled as at 308. A longitudinal slot 309 in the sector permits movement of the sector out of mesh with the ring 302 to allow removal of chambered ring whenever the sector clamping equipment 305 is loosened to permit this shifting of the sector. At this upper end the rock shaft 306 carries a crank 310 which is link-connected, as at 311, to a crank arm 312 secured upon a rock shaft 313. The rock shaft 313 is equipped with oppositely directed crank arms 314 each carrying a roller 315 engageable by one of the cam surfaces 316, 317 formed on the cam and cover plate 36 hereinbefore referred to. The cam surfaces 316 and 317 serve through the connections referred to to impart oscillatory movements to the actuator ring for alternately forcing the container gripping and sealing sectors against the upper portion of each container as it is being vacuumized and then releasing this container gripping engagement after completion of each function. See Figures 2, 19 and 20.

The gripping and sealing of the containers is effected by grip ring sectors 318 which are slidably mounted in the ring chamber surrounding the openings 298. Each of the sectors is composed of upper and lower sections between which is secured the body portion 319 of a rubber grip section from which a flexible grip lip portion 320 extends inwardly for engagement with the external surface of a container to be vacuumized. Each sector 318 has upper and lower ear extensions 321 at one end, and similar upper and lower ear extensions 322 at its other end. Each set of ears 321 and 322 of each sector is pivotally connected to the long leg 323 of a bell crank lever pivotally mounted, as at 324, in the ring chamber and having its short leg 325 pin and slide block connected, as at 326, to a set of upper and lower spaced ears 327 projecting inwardly from the actuator ring 302. See Figure 19.

It will be obvious that whenever the ring 302 is moved in one direction it will swing the bell crank legs 323 outwardly and withdraw the grip sectors from engagement with the container, and whenever this ring is moved in the opposite direction said legs 323 will be swung inwardly to cause the sectors 320 to yieldably grip the container and seal the vacuumizing and sealing chamber 228 against ingress of air. It will be observed that the legs of each bell crank lever connected with an ear set 321 bear less obtuse angular relation than do the legs of each bell crank lever connected with an ear set 322. It will also be observed that the ear sets 321 are longer than the ear sets 322. By reason of the provision of this particular arrangement of the parts, the gripping sectors 320 are caused to move inwardly and outwardly always in substantially concentric relation with the external surfaces of containers presented at the closing station.

The seaming head and its casing are vertically adjustably supported on the superstructure 8 so as to permit vertical movement thereof relative to the container supporting pad, thereby to adapt the machine for use in vacuumizing and closing containers of different heights. This is an expedient well known in the art and in this particular illustration the seaming head assem-

bly is vertically adjustably supported, as at 323, on adjustment screws 329 held captive and rotatable in bearings 330 in the frame portion 8. Rotation may be imparted to the screws 329 through a worm gear couple 331 by a hand wheel 332. See Figure 1.

Operation

In the operation of the machine, the filled containers are fed onto the block chains 106 by which they are deposited onto the single feeder chain 108, the timing screw 112 serving to intercept and space the containers properly for being received on said single feeder chain. As the spaced containers approach the end of the feeder chain 108 they are deflected laterally by the laterally jogged wall portions 113 to be centered over the conveying pins 119 projecting from the conveyor chain 120 to be fed individually thereby onto the lifting and lowering pad at the closing station 103.

As each container approaches the closing station 103 it engages and displaces the valve actuating mechanism control setting wall 254 and shifts the coupler member 242 into its effective position so that when the actuator member 231 is moved downwardly by the cam groove 34 the D-valve 236 will be moved to its lowered position to bring about communication between the vacuum source chamber 232 and the vacuumizing chamber 231 which communicates with the vacuumizing and seaming chamber 228.

Just before this communication of the vacuumizing chamber 228 with the vacuum source is completed, the pad 185, 188 is lifted by the cam groove 26 to present the upper extremity of the container and a cover picked up by the container and loosely resting thereon in the vacuumizing chamber 228. After this is accomplished by the lifting surfaces 216 and 217 of the cam groove 26, and while the container supporting pad is being held in this elevated position by the dwell portion 218 of this cam groove, the segment actuator 302 is shifted by the cam and movement transmitting connections 36, 314, 312, 311, 310, and 304 to swing the bell crank lever legs 323 inwardly and effect a tight gripping of the flexible and yieldable segments 320 against the external surfaces of the container and efficient sealing of the vacuumizing chamber from the atmosphere.

After the vacuumizing of the container has been completed, the portions 219 and 220 of the cam groove 26 function to additionally lift the container supporting pad so as to force the upper extremity of the container and the end closure thereon against the stationary chuck 260. This slight additional upward movement of the container is permitted by a slight upward flexing of the sealing segment lip portions 320. After the container is thus chucked, the control cam 277 causes the seaming rollers to engage and seam-seal the container. Following the sealing of the container, the seaming rollers are retracted, and by reverse action of the parts previously described, the sealing segments 320 are retracted, the knockout pad 264 is lowered to assure removal of the container from the chuck, and the container supporting pad 104 is lowered to permit the oncoming conveyor pin 119 to pick up the vacuumized and closed container and deliver it onto the feedout table 101 to be moved along by the feedout devices hereinbefore described in detail.

It is to be understood that as the container

supporting pad is moved upwardly, the clamp jaws 189, 190 are caused to grip the sides of the container at the bottom by the spring 195, and as the pad is lowered these jaws are supported by the spring equipment 191, the tappet 192 being displaced against the action of the spring 195 by the cam equipment 197.

It is to be understood, of course, that prior to the lifting of the upper end portion of each container into the vacuumizing and sealing chamber 228, a container cover or end closure is fed onto the receiving ledge 333 of the container rounding ring 301 so that the cover will be picked up by the flanged upper end of the container and supported loosely thereon in the vacuumizing chamber 228 prior to the chucking of the container and during the drawing of the vacuum in said container. These end closures can be fed individually and at the proper time through a suitable side opening in the bottom plate 300 by any suitable form of end closure feeding means, and since the particular structure of such feeding means forms no part of the present invention, it is deemed unnecessary to disclose and describe in detail the end closure feeding equipment. The provision of container rounding rings seated, as at 333, also is well known in the art and examples of end closure feeding equipments which might be employed for delivering end closures serially to the ring seat 333 are to be found in the U. S. Letters Patent 1,387,098 issued to Bratt and Fluck on Aug. 9, 1921, and in U. S. Letters Patent 1,653,557 issued to Fink on Dec. 20, 1927. Obviously the end closures are individually fed onto the ring seat 333 prior to lifting of the containers into rounding contact with the ring and at a time when the knockout pad 264 is elevated above said ring seat.

While the present disclosure is directed particularly to valve controlled means for evacuating the chamber 228, it is intended that the invention should be considered as broadly comprehending no can no valve actuation in valve controlled means for displacing air from the filled containers in said chamber whether it be by the creation of a vacuum in said chamber or by introduction of a gas therein in a manner for displacing air from the containers.

It is of course to be understood that the details of structure and arrangement of parts may be variously changed and modified without departing from the spirit and scope of my invention.

I claim:

1. In a machine of the character described, a casing open at its bottom and forming a filled container vacuumizing chamber therein, container sealing means in said chamber including a chuck and seaming mechanism, a container supporting pad, a plunger on which said pad is mounted vertically reciprocable for lifting filled containers into and lowering vacuumized and sealed containers from said chamber, means for feeding filled containers onto said pad, a plate partially closing the bottom of the chamber and having a central opening therein for passing containers being lifted or lowered relative to said casing, yieldable means disposed about said central opening and engageable in embracing contact with a container lifted into the chamber for sealing the chamber against ingress of air, means operable in timed relation to the lifting of said pad for causing said chamber sealing means to yieldably embrace a container lifted

by said pad, means for effecting evacuation of the sealed chamber and the container therein, means for operating the container sealing means for sealing the evacuated container in the sealed chamber, and a rotary grooved cam having a groove portion effective for first lifting the pad a distance to present the container in the vacuumizing chamber for being vacuumized and another groove portion effective for thereafter lifting the container an additional distance while still embraced by said yieldable means for engaging it with the chuck, said yieldable container embracing means being free to yield upwardly as the container is chucked without breaking the seal about said container.

2. In a machine of the character described, a casing having a bottom and an opening in said bottom, said bottom forming a filled container vacuumizing chamber therein, container sealing means in said chamber, a container supporting pad, a plunger on which said pad is mounted vertically reciprocable for lifting filled containers into and lowering vacuumized and sealed containers from said chamber, means for feeding filled containers onto said pad, a plurality of sectors movably grouped about said opening and mounted for movement relative to the bottom of said chamber and having arcuate gripping portions engageable in chamber bottom opening sealing contact with a container lifted into said chamber through said opening and on said pad, means for effecting evacuation of the sealed chamber and the container therein, means for operating the container sealing means for sealing the evacuated container in the sealed chamber, means operable in timed relation to the lifting of said pad for moving said sectors to grip a container prior to the evacuation and sealing thereof and thereafter to release the same, and a rotary grooved cam having a groove portion effective for first lifting the pad a distance to present the container in the vacuumizing chamber for being vacuumized and another groove portion effective for thereafter lifting the container an additional distance while still gripped by said sectors for engaging it with the sealing means, and each said sector having a yieldable and flexible container engaging face portion effective to maintain chamber sealing contact with the container prior to and during the imparting of said additional upward movement to said container.

3. In a machine of the character described, a casing open at its bottom and forming a filled container vacuumizing chamber therein, container sealing means in said chamber, a container supporting pad vertically reciprocable for lifting filled containers into and lowering vacuumized and sealed containers from said chamber, means for feeding filled containers onto said pad, a plurality of sectors movably mounted at the bottom of said chamber and having arcuate gripping portions engageable in chamber sealing contact with a container lifted into said chamber on said pad, means for effecting evacuation of the sealed chamber and the container therein, means for operating the container sealing means for sealing the evacuated container in the sealed chamber, and means for operating said sectors to grip a container prior to the evacuation and sealing thereof and thereafter to release the same, said last named means including actuating levers fixedly pivoted and connected in pairs with the individual sectors and swingable in unison in parallel link fashion as to cause the sectors to move always with their arcuate gripping portions dis-

posed in substantially concentric relation to the container axis.

4. In a machine of the character described, a casing open at its bottom and forming a filled container vacuumizing chamber therein, container sealing means in said chamber, a container supporting pad vertically reciprocable for lifting filled containers into and lowering vacuumized and sealed containers from said chamber, means for feeding filled containers onto said pad, a plurality of sectors movably mounted at the bottom of said chamber and having arcuate gripping portions engageable in chamber sealing contact with a container lifted into said chamber on said pad, means for effecting evacuation of the sealed chamber and the container therein, means for operating the container sealing means for sealing the evacuated container in the sealed chamber, and means for operating said sectors to grip a container prior to the evacuation and sealing thereof and thereafter to release the same, said last named means including a pair of actuating levers connected with each sector, an oscillatable ring, means connecting all said levers with the ring for being moved thereby, and means for oscillating the ring.

5. In a machine of the character described, a casing open at its bottom and forming a filled container vacuumizing chamber therein, container sealing means in said chamber, a container supporting pad vertically reciprocable for lifting filled containers into and lowering vacuumized and sealed containers from said chamber, means for feeding filled containers onto said pad, a plurality of sectors movably mounted at the bottom of said chamber and having arcuate gripping portions engageable in chamber sealing contact with a container lifted into said chamber on said pad, means for effecting evacuation of the sealed chamber and the container therein, means for operating the container sealing means for sealing the evacuated container in the sealed chamber, and means for operating said sectors to grip a container prior to the evacuation and sealing thereof and thereafter to release the same, said last named means including a pair of actuating levers connected with each sector, an oscillatable ring, means connecting all said levers with the ring for being moved thereby, and means for oscillating the ring, a chambered ring removably mounted at the bottom of said vacuumizing chamber and supporting in the chamber therein said sectors and said oscillatable ring, and means for removably mounting said chambered ring at the bottom of said vacuumizing chamber.

6. In a machine of the character described, a casing open at its bottom and forming a filled container vacuumizing chamber therein, container sealing means in said chamber, a container supporting pad vertically reciprocable for lifting filled containers into and lowering vacuumized and sealed containers from said chamber, means for feeding filled containers onto said pad, a plurality of sectors movably mounted at the bottom of said chamber and having arcuate gripping portions engageable in chamber sealing contact with a container lifted into said chamber on said pad, means for effecting evacuation of the sealed chamber and the container therein, means for operating the container sealing means for sealing the evacuated container in the sealed chamber, and means for operating said sectors to grip a container prior to the evacuation and sealing thereof and thereafter to release the same, said

last named means including a pair of actuating levers connected with each sector, an oscillatable ring, means connecting all said levers with the ring for being moved thereby, and means for oscillating the ring, a chambered ring removably mounted at the bottom of said vacuumizing chamber and supporting in the chamber therein said sectors and said oscillatable ring, and a bottom plate removably mounting said chambered ring at the bottom of said vacuumizing chamber and having a central opening therein for passing containers being lifted or lowered relative to said vacuumizing chamber and downwardly flared and sized to engage and round up any out of round containers lifted into said vacuumizing chamber.

7. In a machine of the character described, a casing open at its bottom and forming a filled container vacuumizing chamber therein, container sealing means in said chamber, a container supporting pad vertically reciprocable for lifting filled containers into and lowering vacuumized and sealed containers from said chamber, means for feeding filled containers onto said pad, a plurality of sectors movably mounted at the bottom of said chamber and having arcuate gripping portions engageable in chamber sealing contact with a container lifted into said chamber on said pad, valve controlled means for effecting evacuation of the sealed chamber and the container therein, means for operating the container sealing means for sealing the evacuated container in the sealed chamber, and means for operating said sectors to grip a container prior to the evacuation and sealing thereof and thereafter to release the same, said last named means including a pair of actuating levers connected with each sector, an oscillatable ring, means connecting all said levers with the ring for being moved thereby, and means including a common rotary cam for operating the oscillatable ring and said evacuation controlling valve in timed relation.

8. In a machine of the character described, a casing open at its bottom and forming a filled container vacuumizing chamber therein, container sealing means in said chamber, a container supporting pad vertically reciprocable for lifting filled containers into and lowering vacuumized and sealed containers from said chamber, means for feeding filled containers onto said pad, a plurality of sectors movably mounted at the bottom

of said chamber and having arcuate gripping portions engageable in chamber sealing contact with a container lifted into said chamber on said pad, means for effecting evacuation of the sealed chamber and the container therein, means for operating the container sealing means for sealing the evacuated container in the sealed chamber, and means for operating said sectors to grip a container prior to the evacuation and sealing thereof and thereafter to release the same, said last named means including a pair of actuating levers connected with each sector, an oscillatable ring, means connecting all said levers with the ring for being moved thereby, and means for oscillating the ring, a chambered ring removably mounted at the bottom of said vacuumizing chamber and supporting in the chamber therein said sectors and said oscillatable ring, and a bottom plate removably mounting said chambered ring at the bottom of said vacuumizing chamber and having a central opening therein for passing containers being lifted or lowered relative to said vacuumizing chamber.

9. In a machine of the character described, a casing open at its bottom and forming a filled container vacuumizing chamber therein, container sealing means in said chamber, a container supporting pad vertically reciprocable for lifting filled containers into and lowering vacuumized and sealed containers from said chamber, means for feeding filled containers onto said pad, a plurality of sectors movably mounted at the bottom of said chamber and having arcuate gripping portions engageable in chamber sealing contact with a container lifted into said chamber on said pad, valve controlled means for effecting evacuation of the sealed chamber and the container therein, means for operating the container sealing means for sealing the evacuated container in the sealed chamber, and means for operating said sectors to grip a container prior to the evacuation and sealing thereof and thereafter to release the same, said last named means including a pair of actuating levers connected with each sector, an oscillatable ring, means connecting all said levers with the ring for being moved thereby, and means for operating the oscillatable ring and said evacuation controlling valve in timed relation.
